GAS RANGE

Stanley H. Hobson, Rockford, Ill., assignor, by
mesne assignments, to Reconstruction Finance
Corporation, Chicago, Ill., a corporation of the
United States

Application April 18, 1934, Serial No. 721,101

10 Claims. (Cl. 158—115)

This invention relates to gas ranges and is more particularly concerned with improvements in the cooking top section.

The salient feature of my invention consists in the provision of a gas supply manifold extending from front to rear through the middle of the burner box with valves tapped therein on opposite sides and detachably connected directly with the cooking top burners, thus affording an extremely simple, compact and economical construction, and one in which the four cooking top burners are of identical construction, interchangeable with one another, and easily removable and replaceable. In other words, the present invention gives the much desired unit design.

One of the principal objects of the invention consists in providing an automatic lighter for the cooking top burners in the form of a combination lighter and burner support. It is an improvement on that disclosed in my prior co-pending applications Serial Nos. 468,283 and 573,595. This lighter is supported at the ends of its arms on the valves, thereby insuring the correct relationship between the burner supporting claws on the ends of the arms and the jets on the valves which discharge into the mixers of the burners, while also insuring the correct relationship between the flash-back jet on each burner and the flash-back passage in the arm of the lighter. Each burner is therefore assured of positive automatic lighting, precisely like every other burner. Furthermore, all of the burners are double burners; that is, they have a center simmer burner embodied therein for use both as a simmer burner and as a lighter, and both sections of each burner are always assured of the correct gas delivery from the jets on the valves, by reason of the fact that each supporting arm rests on a valve.

Another object consists in providing a ring-shaped pilot burner at the center of the lighter supplied with gas from the manifold directly therebeneath and having its circular port in the same close proximity with the inner ends of all of the flash-back passages in the lighter, whereby to insure quick and positive lighting.

The invention is illustrated in the accompanying drawings, in which—

50 Figure 1 is a plan view of the front portion of the cooking top of a gas range embodying my invention, the left hand burner assembly being shown complete with its bowl and utensil support, but the right hand burner having the utensil support removed;

Fig. 2 is a longitudinal section taken approximately on the line 2—2 of Figure 1 with the burners removed;

Figs. 3 and 4 are horizontal sections on the correspondingly numbered lines of Fig. 2, Fig. 3 showing the lighter with all but one burner removed, and Fig. 4 showing the lighter removed better to disclose the manifold and the valves connected therewith as well as their operating means, this view also showing the connections between the oven valve on the manifold and the oven burner and oven regulator;

Fig. 5 is a view of the burner assembly partly in vertical section on the line 5—5 of Figure 1;

Fig. 6 is a horizontal section on the line 6—6 of Fig. 5 looking upwardly;

Fig. 7 is a vertical section on the line 7—7 of Fig. 3 showing the pilot burner and adjacent portions of the lighter;

Fig. 8 is a horizontal section on the line 8—8 of Fig. 7 to better disclose the relationship of the ring-shaped port of the pilot burner to the flash back passages of the lighter;

Fig. 9 is a vertical section on the line 9—9 of Fig. 2 looking at the inside of the control panel to show the valve handle mountings;

Fig. 10 is a horizontal section through one of the valve handle mountings on the line 10—10 of Fig. 9;

Fig. 11 is an enlarged view partly in plan and partly in horizontal section through one of the universal joint operating connections between a valve handle and valve stem; and

Figs. 12 and 13 are sectional details on the correspondingly numbered lines of Fig. 11 looking in the directions indicated by the arrows.

The same reference numerals are applied to corresponding parts throughout the views.

Referring to Figs. 1—5, the numeral 14 designates the cooking top which is of sheet metal and has openings 15 therein for the burners 16. Depressed ledges 17 bound the openings 15 and support sheet metal bowls 18 in which openings 19 of four leaf clover or star shape to conform to the burners 16, are provided for the projection therethrough of the burners (see Fig. 5). Secondary air to support combustion flows upwardly through these openings around the burners. The burners 16 are all double burners, that is, each has a small simmer burner 20 at the center thereof which incidentally also serves as a lighter for the main burner, the lighting being accomplished by the propagation of flame through radial slots 21 in the top of the main burner 16 extending from the annular space 22 around the simmer

burner to the continuous peripheral slot 23 defined between the top and the body of the main burner. Both sections of each burner burn with a sheet flame, the flame of the simmer section being circular and that of the main section star shaped. Secondary air also flows upwardly through the annular space 22 between the burner sections to support combustion at the simmer burner. The upstanding radial ribs 24 on the 10 top of each burner reach to a plane above the cooking top 14, and utensil supports 25 conformed to the outline of the burners as shown in Figure 1 have the tops thereof slightly above or level with the burners for proper support of the 15 utensils, as indicated in Fig. 5, and are supported on the cooking top by legs 26 radiating from the supports and fitting in depressions 27 in the marginal portions of the bowls 18 for proper registration of the parts. Downward projections 20 28 on two legs of each utensil support enter holes 29 provided therefor in the cooking top to further assure proper registration of the bowl and support with the burner and to prevent slippage of the support out of position when a utensil is slid 25 across the top thereof. So much for a general understanding of the type of stove to which the present invention relates; it may be called a semi-closed top stove, because while the cooking top 14 is closed, the bowl 18 and utensil support 25 30 cooperating with each burner 16 and its sub-burner 20, form a heat concentrating unit for efficiently heating a utensil placed over the burner, while allowing final escape of the products of combustion to the atmosphere, instead of 35 having the products conducted under the cooking top to a discharge flue. It should, however, be understood that the present invention is not limited to application to this type of stove, but might be applied to a gas range having an open 40 or closed cooking top.

Central manifold

The burner box compartment beneath the 45 cooking top is closed at the front by a wall 30 and at the back by the back wall 31 of the range. The gas supply manifold 32 in accordance with my invention, extends through the middle of the burner box from front to back. It is preferably 50 supported from the cooking top on two hangers 33 and 34 near the front and rear ends, respectively, the rear end projecting through an opening in the back wall 31 for connection with the line. The manifold 32 supplies gas to the cooking 55 top burners 16 and their simmer burners 20 through valves 35 tapped into the manifold from opposite sides, as clearly appears in Figs. 3 and 4. These valves are of the rotary disk type and each 60 has two jets 36 and 37 communicating with passages in the body or stator to deliver gas to the mixers 36' and 37' for the two sections of a burner (see Fig. 5). The rotary disk or rotor 38 of each valve is turned by means of a stem 39 and has passages therein registering with the 65 passages in the body in different positions so as to deliver gas first to the jet 37 alone for lighting of the simmer burner 20, and thereafter, upon further turning of the disk 38, to the both jets, to light the main burner 16, and then, upon 70 further turning of the disk, the main burner 16 has more and more gas supplied thereto, while the simmer burner burns with an unchanged flame. The valves 35 are furthermore so constructed that a detent drops into a recess in the 75 turning of the disk 38 to denote the position at

which gas is delivered to the simmer burner alone. The action of the detent is perceptible to the operator in turning the handle 40 connected with the valve through a rod 41. There are four handles for the four cooking top burners, and a like number of rods 41 and 41', the rods 41 being longer than the rods 41' but otherwise of the same construction, two long rods 41 being required to reach the valves for the two rear burners, and two short rods 41' being required to operate the 10 valves for the front burners. The rods 41 are extended between the jets 36 and 37 of the front valves, as indicated in Fig. 5, also see Fig. 4.

The fact that the manifold 32 is centrally located and has the valves 35 projecting from opposite sides thereof for direct communication with the mixers of the burners makes it possible to have all of the burners of identical construction, interchangeable with one another. In other words, this gives the much desired unit design. It 20 also results in a saving in cost and a generally improved and better appearing construction, and one in which the burners, as will soon appear, are quickly and easily removable and replaceable for inspection and cleaning. 25

Oven valve mounting

A special valve 42 is provided on the front end of the manifold 32 for control of the oven burner 43 and its pilot burner 44. The valve has its inlet coupled directly to the front end of the manifold, as indicated at 42' and has pipes 45 and 46 communicating with outlet passages in the valve, the pipe 45 supplying gas to the oven burner 43 through an oven regulator 47 which has a 35 thermostat 48 extending therefrom into the oven that is heated by the burner 43. The pipe 46 communicates directly with the pilot burner 44. The valve 42 similarly to the valves 35 is of the rotary disk type, and the pipes 45 and 46 extend from the stator thereof, the rotor 48 having passages therein to register with the passages in the stator when the rotor is turned by means of its stem 49 and handle 50. Now, a dial 51 bearing oven temperature graduations is turned with the 45 rotor 48 and indicates the setting for the oven regulator 47, the rotary temperature adjustment cam 52 of said regulator being turned with the stem 49 through a rod 53 having a universal joint connection at 54 with the rear end of the stem 50 50 49 projecting from behind the stator of the valve 42, and having a similar universal joint connection at 55 with the rotary cam 52. The dial 51 is visible through a window 56 in the control panel 57 on the front wall 30, and in operation, the 55 handle 50 is turned in a clockwise direction from the "off" position to, first of all open the valve 42 for the delivery of gas to the oven burner 43 and pilot burner 44, and then by further turning of the handle 50, the oven regulator 47 is set for 60 a selected oven temperature indicated by the dial 51. An arm 58 behind the dial 51 is turned with the dial and serves by engagement with either one of the two pins 59 provided on the stator of the valve 42 to limit rotation of handle 50. 65

The mounting of the oven valve 42 on the front end of the manifold 32, it should appear from the foregoing description, is highly advantageous not only because it simplifies the connection of the valve with the manifold and provides good support for the valve, but also because the stem 49 can project directly through the panel 57 for operation by means of handle 50 mounted directly thereon, and the oven temperature dial 51 is at the same time disposed directly behind the 70 75

5 window 56 in the panel 57 to indicate the setting of the oven regulator 47. This location of the valve 42 also enables the simple operating connection 53 between the rear end of the stem 49 of the valve and the rotary cam 52 of the oven regulator 47.

Combination lighter and burner support

The four valves 35 have saddles, 60 provided thereon next to shoulders 61 for the support of the combination lighter and burner support indicated generally by the numeral 62. The device 62 for convenience will hereinafter be referred to as the lighter. The lighter is a one-piece casting 15 consisting of a hollow casing 63 for a pilot burner 64, and radiating arms 65 cast integral with the casing 63 and having flash back passages 66 formed therein. The arms 65 have claws 67 provided on the outer end thereof to support the burners 16; in other words, the arms 65 serve both as flash tubes and burner supports. Bosses 20 68 are formed on the arms 65 near the claws 67 and have downwardly projecting forks 69 thereon to straddle and rest on the saddles 60 in front of shoulders 61 for support of the lighter 62. Bolts 70 have their headed upper ends bearing 25 against the underside of the cooking top 14 and the threaded lower ends of these bolts pass through openings in the webs 71 formed on the lighter between the arms 65, and nuts 72 thread 30 on the bolts and are arranged to be tightened against the webs 71 so as to exert pressure downwardly on the lighter 62 to seat it firmly on the saddles 60. Other nuts 73 are threaded on the 35 lower ends of the bolts and tightened against the webs 71 after the adjustment of nuts 72, so as to lock the parts in adjusted condition and prevent accidental loosening of the lighter 62. Any other means of holding the lighter in place could be provided, such, for example, as U-bolts extending upwardly from the manifold 32 through holes in the webs 71. However, the bolts 70 are 40 preferred because they simplify assembling.

The claws 67 extend outwardly and upwardly with respect to the outer ends of the arms 65, as best appears in Fig. 5, for engagement with the bottoms of the burners 16 to support the latter high enough so that the jets 14 of the simmer burners 20 are disposed in about the same horizontal plane with the bottoms of the flash back passages 66. Each claw 67 provides two fingers for engagement in recesses 75 provided in the bottom of each burner 16 as shown in Fig. 6, whereby to locate the burner on the claw and prevent shifting of the burner to one side or the other once it has been set down on the supporting claw. There are two upward projections 76 on the two fingers of each claw 67 to provide two of the three points of support for a burner, the burner being arranged to fulcrum with respect to these two points 76, and being overweighted on one side of these fulcrums sufficiently to assure engagement with a downwardly projecting flange 77 constituting the third point of support and formed on the boss 68 next to the fork 69. Viewing Fig. 5, the burner 16 tends to turn in a counter-clockwise direction about the points 76 as fulcrums, thus causing the mixer 37' of the simmer burner 20 to engage the bottom of flarige 77. The three point support definitely insures the location of each burner in the proper plane with respect to the cooking top 14 and bowl 18 and utensil support 25.

In operation, when the valve 35 of a burner is
75 opened by turning the disk 38 thereof, gas is first

discharged through the jet 31 into mixer 37' of the simmer burner 20. This gas issues from the burner 20 and at the same time from the jet 74 into the flash back passage 66 of the lighter 62. The gas issuing from jet 74 charges the flash back passage sufficiently for ignition to occur in the housing 63 by the pilot burner 64, and when that occurs, there is a flash back of sufficient force to easily insure lighting of the simmer burner 20 and jet 74. The "pressure wave" or flash back is of sufficient violence that I have found it advisable to provide a vent 78 in the wall of the flash back passage 66 at the bend in the outer end (see Fig. 3) and this vent is therefore in the direct path of the pressure wave moving outwardly from the housing 63 to the simmer burner 20, and enough pressure is spent or dissipated through the vent 78 so that the burner 20 and jet 74 are sure of ignition and the flame at the jet 74 will not be snuffed out. Snuffing out this flame would only give rise to re-charging of the passage 66 again and again to no purpose. Now, the simmer burner can be left burning alone so long as may be required, in the event simmer action is desired, but if the main burner 16 associated with the simmer burner is to be lighted, the disk 38 of the valve 35 is turned further to cause discharge of gas through jet 36 into mixer 36' of the main burner 16. Gas issuing from the continuous slot 23 at the periphery of the burner 16 is immediately ignited by the simmer burner 20 by flame propagation through the slots 21. The automatic lighting of the simmer burner occurs instantly and by the time the disk 38 is turned far enough to supply gas to the main burner 16, the simmer burner has been lighted and serves as the lighter for the main burner. In other words, the operator need only operate the valve in one movement when he is going to light the main burner 16 along with the simmer burner 20; he does not have to stop to wait for the lighting of the simmer burner before turning the valve further to light the main burner. When the simmer burner 20 is to be used alone, the operator can tell by the detent action incorporated in the valve 35 (not shown) when he has turned the valve disk 38 far enough, and there is, therefore, no likelihood of turning the disk too far and thus supplying some gas to the main burner 16. The jet 37 for charging the simmer burner is specially constructed to give two-stage aeration, the first stage being by entrainment of air with the gas through the transverse hole 79 (see Fig. 5), and the second stage being by entrainment of additional air with the mixture discharged from the jet 37 into the mixer 37'. This results in the proper stabilization and consequent proper functioning of the simmer burner despite the fact that a relatively small amount of gas is delivered to the simmer burner.

It should be apparent from the foregoing description that the lighter 62 supports each of the burners 16 rigidly and with the charging jet 74 of the simmer burner 20 in proper relation to the flash tube associated therewith for quick and positive lighting. The proper relationship is assured because of the fact that the flash tube supports the burner. In other words, the relationship of each burner to its flash tube is entirely independent of the relation of said burner to the other burners; in previous lighters where the lighter had flash tubes arranged to rest on the burners, it presupposed the location of all of the burners in exactly the same plane, and one or more were always apt to be above or below the plane of the others and in that way the flash tubes for cer- 60 65 70 75

tain burners were not properly positioned with respect thereto for quick and positive lighting. Furthermore, since the burner supporting lighter is supported by the valves, there is every assurance that the mixers 36' and 37' of the burners will be properly disposed with relation to the jets 36 and 37, respectively, provided on the valves. The present lighter and its novel combination with the valves as herein disclosed are responsible as previously indicated for the unit design, which is one of the principal objects of this invention.

Ring-shaped pilot burner

Referring to Figs. 7 and 8, the pilot burner 64 has a ring-shaped port 80 disposed substantially equi-distant from the inner ends of all of the flash back passages 66 in the lighter 62, as clearly appears in Fig. 8. The circle described by this port is substantially concentric with the circular inside of the housing 63 and is of sufficient radius to bring the port in close proximity with the inner ends of the passages for quick and easy lighting of gas conducted from a burner through a passage to the housing 63. In the past where an ordinary small jet was provided for the pilot light, it was practically impossible to have the jet accurately centered in all cases, and the result was that only those burners whose flash back passages were close enough to the jet for lighting, would be served properly; the others would not be lighted satisfactorily, if at all. Then, too, the size of the single flame in such an installation made considerable difference in lighting. These objections are all eliminated with my invention, because the continuous circular or ring-shaped port is brought close enough to each and every flash back passage to obtain the same positive lighting for each and every burner. The lighting is furthermore unaffected by a change in the size of the flame. Another objection to the old construction was that when the pilot light was cut down to a small size for economy, it was quite apt to be blown out by a sudden gust of air or by the pressure wave in the flash back lighting of a burner. That objection is entirely eliminated with the ring-shaped pilot burner because even though the flame is extinguished at one point of the circle by reason of a gust of air or the action of a pressure wave, the rest of the ring-shaped pilot light is not disturbed or, at least is not extinguished, and the full circle of flame will be immediately thereafter built up again. It is practically impossible to extinguish this burner with the ordinary wind tests, regardless of a low flame. The importance of this cannot be over-emphasized, especially in the case of ranges equipped with automatic clock controls where the continued burning of the pilot light is so completely relied upon. The burner 64 has the body 81 thereof formed with a circular raised portion 82 to fit inside the housing 63 for accurate location of the burner, and bolts 83 passed through the webs 71 of the lighter and through the projecting lugs 84 of the burner serve to fasten the burner in place. A Bunsen mixer 85 is connected with the burner as appears in Fig. 7, and is supplied with gas from the manifold 32 through the tube 86 and fitting 87. The latter is tapped into the manifold and has a screw adjustment 88 for controlling the delivery of gas to the pilot burner 64.

Valve operating means

Referring to Figs. 4 and 9-13, it will be observed that the valves 35 are all operated by

handles 40 through rods 41-41' detachably connected at opposite ends with the stems 39 of the valves and the shanks 89 of the handles. The rods are formed at both ends with tapered portions 90 ending in crossheads 91 of approximate cylindrical form. At the middle of each crosshead, that is, on the axis of the rod, an enlarged ball portion 92 is provided. With this construction the ball-shaped portion at one end of the rod is slidably received in an axial bore 93 in the valve stem 39, and the ball-shaped portion at the other end of the rod is similarly received in an axial bore 94 in the handle 40, whereby to center the one end of the rod accurately with respect to the valve stem and the other end of the rod with respect to the handle. The valve stem is slotted longitudinally as at 95 to slidably receive the ends of the crosshead 91, and longitudinal slots 96 are provided in the handle to slidably receive the crosshead 91 on the other end of the rod. A certain range of angular movement of the rod in one plane with respect to the valve stem and handle is allowed by reason of the crossheads being slidable in the slots 95 and 96, and angular movement of the rod in a transverse plane is permitted by reason of the crossheads being cylindrical and therefore free to oscillate in the slots. The movement permitted in one plane is limited by the slots 96 which, as appears in Fig. 13, is made wider than the end 30 of the rod. A predetermined range of movement in the other plane is secured by the flaring of the outer end of the slots 95, as indicated at 97, and the flaring of the outer end of the slots 96 as at 98. The fact that the ends of the rods 35 are tapered to such a reduced width as appears in Fig. 11 is, of course, also responsible for the construction permitting an appreciable range of universal movement. The construction besides being so simple and economical to manufacture 40 also has the advantage of easy assembling and disassembling; the panel 57 carrying the handles 40 is removable upon removal of the four wing nuts 99 threaded on studs 100 projecting inwardly from the panel through the front wall 30 and cross-piece 101, and in such removal and replacement, the front ends of the rods 41-41' slide easily out of or into the shanks of handles 40. The rods are likewise easily connected to or disconnected from the stems 39 of the valves. 50

The handles 40 are for the sake of appearance preferably molded of plastic material. A bearing portion 102 is formed on the shank thereof between an annular groove 103 and an annular shoulder 104. With this construction, 55 the shank is then adapted to be inserted in a circular hole 105 in the panel 57, and a U-shaped spring wire clip 106 is snapped into the groove 103 as clearly appears in Figs. 9 and 10, whereby to detachably secure the handle in place, with 60 the shoulder 104 in abutment with the outside of the panel and the clip 106 in abutment with the inside. The shank of the handle is arranged to turn with respect to the clip, the latter being held against turning by means of a 65 projection 107 on the inside of the panel 57. The end of the spring clip 106 is bent at right angles, as clearly appears in Fig. 10 so that it may be moved into or out of position easily by 70 finger pressure when the handle is being installed or removed.

It is believed the foregoing description conveys a good understanding of all of the objects and advantages of my invention. The appended 75

claims have been drawn with a view to covering all legitimate modifications and adaptations.

I claim:

- 5 1. In a gas stove, the combination with the burners of the cooking top, of an automatic lighter comprising a pilot light casing having flash tubes extending therefrom toward the different burners, a gas supply manifold below the cooking top having valves projecting therefrom toward the different burners, means whereby the valves support the lighter by engagement with the flash tubes so that the lighter is disposed in a predetermined position with reference to the cooking top, and means for supporting the burners 10 on the ends of the flash tubes in positions adjacent the valves to receive gas therefrom.
- 15 2. In a gas stove, the combination with the burners of the cooking top, of an automatic lighter comprising a pilot light casing having flash tubes extending therefrom toward the different burners, a gas supply manifold below the cooking top having valves projecting therefrom toward the different burners, supports on the valves detachably engaged by portions on the 20 flash tubes whereby to support the lighter in a predetermined position with reference to the cooking top, means extending between the cooking top and the lighter and serving to hold the latter against displacement from the supports, 25 and means for supporting the burners on the ends of the flash tubes in positions adjacent the valves to receive gas therefrom.

3. In a gas stove, the combination with the burners of the cooking top, of a gas supply manifold below the cooking top extending between the burners and having valves communicating therewith and extending from opposite sides thereof toward the burners to deliver gas thereto, an automatic lighter comprising a central pilot 35 light casing having flash tubes radiating therefrom toward the different burners, said lighter being supported on the manifold so that the pilot light casing is directly over the manifold and the ends of the flash tubes are over the various valves, 40 a pilot burner in said casing having direct communication with the manifold therebeneath, and means for supporting the burners on the ends of the flash tubes and in communication with said valves.

- 45 4. In a gas stove, the combination with the burners of the cooking top, of a gas supply manifold centrally disposed with reference to the cooking top and below the same, valves extending horizontally from opposite sides of the manifold toward the different burners, each of said valves 50 having a supporting saddle portion adjacent a locating shoulder, a lighter for said burners comprising a pilot light casing with flash tubes extending therefrom, the latter having downwardly 55 reaching forked projections to straddle and rest on the saddle portions in engagement with said shoulders, whereby to support the lighter in a substantially horizontal plane at a predetermined elevation relative to the cooking top and valves, 60 and means for supporting the burners from the lighter in operative relation to the lighter and to said valves.

- 65 5. In a gas stove having a cooking top, the combination of a gas supply manifold below the cooking top, a plurality of cooking top burners, a plurality of valves projecting from the manifold toward the burners, a lighter comprising a pilot light casing with flash tubes extending therefrom, 70 said lighter being suitably supported above the manifold and having the ends of the flash tubes

projecting over the valves, each flash tube end being disposed in the same relation to a valve associated therewith, said plurality of cooking top burners being of like construction and interchangeable with one another, and means on the 5 burners and the ends of the flash tubes, whereby the burners are all suspended solely upon the lighter so that each communicates in the same way with the lighter for lighting, while communicating in like manner with a sub-adjacent valve 10 to receive gas therefrom.

6. In a gas stove comprising a cooking top, burners therefor, a gas supply manifold beneath the cooking top having valves extending therefrom toward the different burners to supply gas 15 thereto, and a combination lighter and burner support beneath the cooking top comprising a pilot light casing having flash tubes extending therefrom toward the burners to conduct gas from the burners to the pilot light for ignition, 20 the same being supported on said valves and having means on the ends of the flash tubes for supporting the burners in operative relation to said valves and also to permit lighting thereof.

7. In a gas stove comprising a cooking top, 25 burners therefor, a gas supply manifold beneath the cooking top having valves extending therefrom toward the different burners to supply gas thereto, an automatic lighter comprising a pilot light casing having flash tubes extending therefrom toward the different burners, means for supporting the lighter by its flash tubes on the aforesaid valves, and means for detachably connecting the burners with the outer ends of said 30 flash tubes for support of the burners thereon in operative relation thereto and to said valves.

8. In a gas stove, the combination with the burners of the cooking top, of a gas supply manifold below the cooking top having valves with jets to deliver gas to the burners, a lighter for 40 said burners comprising a central pilot light casing having flash tubes extending therefrom toward the burners, said lighter being supported on the manifold in a substantially horizontal plane at a predetermined elevation with reference to the cooking top and with its pilot light casing in juxtaposition with the manifold, there being a pilot burner in said casing supplied with gas from the manifold, and means for supporting the first named burners on the outer ends of said 45 flash tubes in a substantially horizontal plane at a predetermined elevation relative to the cooking top and in operative relation to the flash tubes and valve jets.

9. In a gas stove, the combination with the 55 burners of the cooking top, of a gas supply manifold below the cooking top having valve elements with jets to deliver gas to the burners, a lighter for said burners comprising a central pilot light casing having flash tube elements extending 60 therefrom toward the burners, said lighter being supported on the manifold in a substantially horizontal plane at a predetermined elevation with reference to the cooking top, said flash tube elements and valve elements being thereby arranged in juxtaposition, and means for supporting each cooking top burner on one of said flash tube and valve elements in communication with the valve element for gas supply and with the flash tube element for discharge of gas thereto 65 and flash back lighting therefrom.

10. In a gas stove, the combination with the burners of the cooking top, of an automatic lighter comprising a pilot light casing having flash tube elements extending therefrom toward 75

the different burners, a gas supply manifold below the cooking top having valve elements projecting therefrom toward the different burners, means whereby the valve elements support the lighter by engagement with the flash tube elements so that the lighter is disposed in a predetermined position with reference to the cooking top, the flash tube elements and valve elements being

thereby arranged in juxtaposition⁶³ and means for supporting each cooking top burner on one of said flash tube and valve elements in communication with the valve element for gas supply and with the flash tube element for discharge of gas 5 thereto and flash back lighting therefrom.

STANLEY H. HOBSON.
